CLAIM

The ornamental design for a container for medical products, as shown and described.

DESCRIPTION

FIG. 1 is a top and front perspective view of a container for medical products showing my new design;
 FIG. 2 is a front elevational view thereof, the rear elevational view being a mirror image of that shown;
 FIG. 3 is a side elevational view thereof, the opposite side view being a mirror image of that shown;
 FIG. 4 is a top plan view thereof; and,
 FIG. 5 is a bottom plan view thereof.
